UNITED STATES PATENT OFFICE.

ALFRED LEHNER, OF CHEMNITZ, GERMANY.

SPINNING MACHINE.

Application filed June 5, 1925, Serial No. 35,134, and in Germany June 12, 1924.

My invention refers to spinning machines, more especially for spinning artificial silk. It is an object of my invention to provide means whereby the lubrication of such machines is improved so as to reduce the wear to which the movable parts of the machines are exposed.

In the spinning machines used hitherto for the spinning of artificial silk the driving device for the thread guide is located in the interior of the machine; the starting of the reciprocating movement of the thread guide arranged at the top of the machine is effected by a shaft extending through the lower part of the machine frame. Each separate bobbin spindle is guided by two bearings each of which must be oiled separately. As a rule a machine of this kind has 200 bobbins, requiring 400 bearings, so that there are 400 lubricating points for the bobbin spindles alone, and 400 wheels to be oiled for driving these bobbin spindles. In addition there are numerous bearings for the shafts extending longitudinally through the machine which drive the wheels of the bobbin spindles; for which reason there are a large number of bearings and lubricating points for effecting and transmitting the movement of the thread guide.

Consequently the spinning machines for artificial silk have the considerable disadvantage of the extremely large number of bearing points and machine parts to be lubricated, whereby the efficiency of operation is unfavorably influenced.

A further disadvantage of the known artificial silk spinning machine consists in that the movable parts thereof operate continuously in an atmosphere of sulphuretted hydrogen and are therefore exposed to considerable wear. For this reason the efficient and uninterrupted lubrication of the moving part plays a much more important part than in machines which operate under normal conditions.

According to the present invention I do away with these drawbacks, not only in the bobbin spinning machines, but also in the machines operating according to the centrifugal method. In the bobbin machines the threads issuing from the apertures of the spinning nozzle are taken up by a spinning bobbin, while in the machines operated according to the centrifugal method

the spun thread is drawn over a guide roller (galette) and thereafter through a glass funnel into the interior of a rapidly rotating centrifuge within which, by reason of centrifugal force, it is deposited on the inner wall, forming a "spun cake" consisting of crossed thread layers.

According to the present invention all the moving parts including the thread receiving and guiding means as well as the mechanisms for driving same closely adjoin each other and these mechanisms run in closed oil casings communicating with one another. The arrangement here is such that the oil required need only be filled up in one of these casings in order to provide all the lubricating points with the required quantity of oil. By enclosing all parts of the driving mechanism in closed containers the unfavorable action of the sulphuretted hydrogen and acid vapours is excluded.

In addition to this important advantage, which is obtained by the periodic filling up of the oil being required only at a single, easily accessible point of the machine, the consumption of lubricant is reduced to a minimum. The security that each bearing is continually supplied with lubricant is absolutely warranted; the necessity of hand lubrication is obviated. I prefer mounting the driving mechanisms and lubricating tanks in the top portion or on top of the machine frame, the tank which encloses the driving mechanism for the thread receiving means at the same time acting as a reinforcing member for the frame, and the tank which surrounds the driving mechanism for the thread guiding means, being placed on top of the tank first mentioned and being supplied with oil from this latter by means of suitable conveying mechanism.

In the drawings affixed to this specification and forming part thereof, two machines embodying my invention are illustrated diagrammatically by way of example.

In the drawings—100

Fig. 1 is a cross-section, and

Fig. 2 is a partial longitudinal section of a bobbin spinning machine, while

Fig. 3 is a cross section of a machine operated according to the centrifuging method. 105
Referring first to Figs. 1 and 2 the spinning nozzles 1 are arranged in a well-known manner in a sulphuric acid bath 30 within which

the viscose leaving the nozzles is converted into threads. The thread 31 passes over the two thread guides 33 and 2, carried at the front and rear end of an arm 32 to the bobbin 3. Each bobbin is mounted in a bobbin carrier 4 secured to the bobbin spindle 5; on the opposite end thereof is also mounted a bobbin carrier 4 for the reception of a bobbin. The bobbin spindle 5 extends through a closed casing 6 within which it is mounted in bearings 7. Within the casing there is mounted on the bobbin spindle 5 a worm wheel 8 driven by a worm 9 on a shaft 10; the shaft 10 with worm wheel 9 is also mounted within the casing.

When operating spinning machines for artificial silk the arrangement of the bobbins is, as is well known, such that alternately one bobbin of a row of bobbins rotates whilst the next succeeding bobbin remains empty so that the latter can be brought into operation immediately when the rotating bobbin has been fully wound. Care must therefore be taken that, if the uneven bobbins are rotating, the even bobbins are stationary and vice versa. Whereas the even bobbins 3 are driven by worm wheels 8, 9, the uneven bobbins 3¹ are driven by the worm wheels 8¹, 9¹; the worm wheels 9¹ are mounted on shafts 10¹. All the worm wheels and their driving shafts, as stated, are mounted in closed casings 6.

In the longitudinal direction of the machine there is arranged a number of such closed casings 6 one behind the other. These casings communicate with one another by connecting pipes 12 (Fig. 2). If at an easily accessible point of the machine oil is supplied for lubrication of the machine parts running within casings 6 then the oil level will be the same in all the casings 6 connected together by the connecting pipes 12. The casings 6 therefore not only form the bearing casings for the said parts, but at the same time the lubricating oil containers therefor; at the same time the casings 6 form the upper bracing means for several standards of the machine.

The arms 32, moving on both sides of the machine above the bobbin rows 3 and 3¹, and on which the thread guides 33 and 2 are mounted, are imparted a reciprocating movement by means of which the regular winding of the thread 31 on the bobbins 3 and 3¹ is effected. The two oppositely disposed arms 32 together with the thread guides 2 and 33 are carried by a common rod 13 to which is imparted an oscillating movement transversely to the longitudinal axis of the machine by oscillatory levers 14, 15. On the rod 13 are seated bolts 16 over which engage the forked ends of the rods 14 and 15. The oscillatory lever 14 is secured at its upper end to a transverse shaft 17 which has imparted to it a rocking motion

by a lever 18 controlled by a heart shaped cam 19. This cam is mounted on a transverse shaft 20 driven by means of a pair of spiral gears 21, 22 from a shaft 23 extending in the longitudinal direction of the machine. The second oscillatory lever 15 is not separately driven but serves mainly as a guide. At its upper end 29 it is suspended by the edge of an acid proof metal piece of triangular cross-section. This suspension does not require being lubricated.

The remaining parts of the gear for producing the reciprocating movement of the thread guide are arranged in a casing 24, which is mounted directly above the casing 6. The partition separating the casings 6 and 24 is provided with a slot 25 through which extends a bucket mechanism carried by a chain 26, which is preferably driven by a shaft 20. The object of this bucket mechanism is to raise oil from the lower casing 6 in order to lubricate the driving mechanism contained in the upper casing. The oil raised by the bucket mechanism is partly conducted into a gutter 27 from which the oil passes to the bearing of the transverse shaft 17, the excess oil flowing down to the bottom of the casing 24. As the slot 25 is surrounded by raised edges, the oil in the upper casing 24, will be retained at a level corresponding with these edges, whilst the excess oil flows through the slot 25 into the lower casing 6. The lubrication of the heart shaped cam is effected partly by its point dipping as during rotation into the oil bath of the upper casing 24 and partly by distributing grooves (not shown) similar to the groove 27, which are supplied by the bucket mechanism. The bearing points of the heart shaped cam are lubricated either by the oil flowing down the walls of the casing 24 or also by lubricating grooves receiving oil from the bucket mechanism 26. In this manner all parts of the driving mechanism which effect the oscillatory movement of the thread guides, are lubricated from the common oil bath of the containers 6.

While the casings 6 extending in the longitudinal direction of the machine are arranged one directly behind the other, the casings 24 are spaced apart, for example in such a manner that for each field, corresponding with the length of a longitudinal casing 6, there is provided a casing 24 and a heart shaped cam 19. The transmission of movement from the heart shaped cam 19 to all the reciprocating thread guide rods of the field is effected at both ends of the rod 13, which is directly driven from the heart shaped cam by means of the oscillatory levers 14, 15 to which are secured connecting rods 34 extending in the longitudinal direction of the machine within reach of each of the bobbins 3 and 3¹, each carrying an arm 32 with the thread carriers 33 and

2. The thread guides provided on both sides of the machine move in synchronism in accordance with the oscillatory movement of the rod 13 directly driven by the heart shaped cam.

In the arrangement illustrated there is shown only a simple heart shaped cam 19, which, as is well-known, effects a regular cylindrical winding of the thread on each bobbin 3 and 3¹. If instead of a uniform velocity it is desired to impart to the rod 13 a non-uniform velocity for the purpose of winding less of the thread on the ends of the bobbins than at the middle, an auxiliary cam may be provided in a well-known manner within the casing 24, which, in combination with the main cam, produces the non-uniform movement.

By arranging the driving mechanism for the thread guide movement within the casing 24 there is obtained the advantage that this mechanism being disposed above the machine, is always readily accessible from both sides of the machine, while in previous machines this mechanism was disposed in the interior of the machine frame where access to it was rendered difficult by the spinning nozzles, sulphuric acid troughs, viscose pipes and so forth arranged on both sides. The novel arrangement of this mechanism further affords the advantage that it receives a certain and continuous automatic lubrication from a common oil bath formed by the containers 6 communicating with one another. Finally the arrangement of the driving mechanism in the upper containers 24 permits of a compact arrangement of the bobbins extending along both sides of the machine.

Spinning machines constructed according to the invention therefore are considerably reduced in width, whereby supervision is improved and the possibility of using up the machine space is considerably improved.

As far as the lower casing 26 is not covered by the upper casing 24, it is tightly closed by a cover 28. All parts of the driving mechanism, particularly also the bearing points are removed from the atmosphere of sulphuretted hydrogen; the only bearing point 29, outside the casings 6 and 24 has the form of a knife edge suspension of said proof metal.

In the machine illustrated in Fig. 3 the silk thread issuing from the spinning nozzle (not illustrated) passes in a well-known manner to the guide roller or galette 41 and from here to a vertically moving glass funnel 54 which conducts the thread to the centrifuge 55. The guide rollers together with the corresponding glass funnels and centrifuges are arranged uniformly at both sides of the machine.

The guide rollers 41, at each side of the

machine, are driven by transverse shafts 61 in such a manner that two oppositely disposed guide rollers 41 are mounted on a transverse shaft. The transverse shafts 61 are mounted in an oil box 62 and are driven by bevel wheels 63, running within the oil box, and a longitudinal shaft 64 also mounted within the oil box.

The oil-box extends either along the whole length of the casing or, as described with reference to Figs. 1 and 2, it may be divided into a number of separate casings which communicate with each other by means of a pipe in such a manner that when filled with oil at one point of the machine the oil level will be uniform in all the casings 62.

Below the oil box or each oil box 62 a further closed casing 42 is mounted in the machine frame and in this casing 42 there is mounted the driving mechanism for the up and down movement of the funnels 54 arranged at both sides of the machine. The driving mechanism here consists of a heart shaped cam or eccentric 43, mounted on a shaft 44, rotated by two worm wheels 65, 66 on the shaft 45. The shaft 45 extends in the longitudinal direction of the machine and where the casing 42 and the upper oil casing 62 are divided into sections, it passes through the separate casings. Preferably the number of oil casings 42 arranged one behind the other and connected together by communicating pipes is such, that an oil casing is provided for about three fields consisting for example of six successive spinning cans.

The heart shaped cam or eccentric 43 raises and lowers a slide 46 with which engages a lever arm 47. The latter is mounted on a shaft 48, also extending through the whole machine, which carries a row of arms 49 arranged in pairs diagonally opposite one another. On these arms 49 are suspended by means of chains 50, U-shaped rails 51 which also extend through the whole machine.

While the driving mechanism 43, 44, 65, 66, 45, 48, 46, and 47 is located within the casing or casings 42, the arms 49 with the chains 50 and the U-shaped carriers 51, are mounted outside the casing.

When the heart shaped cam or eccentric 43 rotates, the shaft 48 is imparted a rocking movement which is transmitted to the rails 51 so that these move up and down alternately. For accurately guiding these rails, guides 52 are provided at intervals, preferably on the standards of the machine, on which slide the rollers 67 carrying the rails 51.

The U-rails 51 carry arms 53 on which are mounted the funnels 54; each centrifuge 55 of the machine has a funnel 54 and a cor-

responding arm 53. The centrifuges 55 are rotatably mounted in a casing 56 and 57.

The centrifuges mounted in a casing 56 are driven by a disc 58 which is driven by adhesion by a disc 59, mounted on a shaft 60 extending through the machine, and driven in a well known manner from one of the ends of the machine.

All the bearings carrying the two shafts 60 and serving to drive the separate centrifuges 55 are also arranged in closed oil casings 68, preferably with ring lubricating bearings.

The casings arranged one behind the other 15 in the longitudinal direction of the machine also communicate with one another by means of pipes. Further a pipe may be extended to one end of the machine where it receives the supply of oil and is provided 20 with an inspection glass.

In agreement with the construction, illustrated in Fig. 1 and 2 the oil casings 62 and 42 spaced apart one above the other can be connected by a device for conveying lubricating oil. In the form of construction illustrated provision is made that at the driving side of the machine filling points with inspection glasses are arranged both for the upper casing 62 and for the lower casing 42 30 separately at different levels.

I wish it to be understood that I do not desire to be limited to the exact details of construction shown and described, for obvious modifications will occur to a person 35 skilled in the art.

I claim:

1. Artificial silk spinning machine comprising a machine frame, thread receiving means, thread guiding means, separate 40 mechanisms for driving said receiving and said guiding means respectively all adjoining each other and arranged in the longitudinal direction in the top portion of said frame and common lubricating means for a plurality of driving mechanisms for said receiving means.

2. Artificial silk spinning machine comprising a machine frame, thread receiving means, thread guiding means, separate 50 mechanisms for driving said receiving and said guiding means respectively all adjoining each other and arranged in the longitudinal direction of said frame and common lubricating means for a plurality of driving 55 mechanisms for said receiving means, said driving mechanisms and lubricating means being arranged in the top portion of said frame.

3. Artificial silk spinning machine comprising a machine frame, thread receiving means, thread guiding means, separate 60 mechanisms for driving said receiving and said guiding means respectively all adjoining each other and arranged in the longitudinal 65 direction of said frame, a common

lubricating tank for all said driving mechanisms for said receiving means and several lubricating tanks common to a plurality of driving mechanisms for said guiding means and communicating with one another.

4. Artificial silk spinning machine comprising a machine frame, thread receiving means, thread guiding means, separate mechanisms for driving said receiving and said guiding means respectively all adjoining each other and arranged in the longitudinal direction of said frame and common lubricating means for a plurality of driving mechanisms for said receiving means, said receiving means being arranged in pairs, 70 one on each side of said frame, and a common transversal shaft for the receiving means of each pair.

5. Artificial silk spinning machine comprising a machine frame, thread receiving means, thread guiding means, separate mechanisms for driving said receiving and said guiding means respectively all adjoining each other and arranged in the longitudinal direction of said frame and common 80 lubricating means for a plurality of driving mechanisms for said winding means, said receiving means being arranged in pairs, one on each side of said frame, a common transversal shaft for the winding means of each 85 pair and two shafts forming the said driving means for alternating pairs of winding means and extending in the longitudinal direction of said lubricating means.

6. Artificial silk spinning machine comprising a machine frame, thread receiving means, thread guiding means, separate mechanisms for driving said receiving and said guiding means respectively all adjoining each other and arranged in the longitudinal direction of said frame and common lubricating means for a plurality of driving mechanisms for said receiving means, said driving mechanisms and lubricating means being arranged in the top portion of said 100 frame in superposition.

7. Artificial silk spinning machine comprising a machine frame, thread receiving means, thread guiding means, separate mechanisms for driving said receiving and said guiding means respectively all adjoining each other and arranged in the longitudinal direction of said frame and common lubricating means for a plurality of driving mechanisms for said receiving means, said 115 driving mechanisms and lubricating means being arranged in the top portion of said frame in superposition and a conveyor for supplying the uppermost lubricating means with lubricant from the lower one.

8. Artificial silk spinning machine comprising a machine frame, thread receiving means, thread guiding means, separate mechanisms for driving said receiving and said guiding means respectively all adjoining 120

ing each other and arranged in the longitudinal direction of said frame and common lubricating means for a plurality of driving mechanisms for said receiving means, said 5 driving mechanisms and lubricating means being arranged in the top portion of said frame in superposition, a conveyor for supplying the uppermost lubricating means with lubricant from the lower one and 10 means associated with said upper lubricating means for distributing the lubricant.

9. Artificial silk spinning machine com-

prising a machine frame, thread receiving and thread guiding means arranged on either side of said frame, vertically reciprocable funnels associated with said receiving means, two lubricating tanks superposed on top of said frame and a heart-shaped rotary cam member in the lower of said tanks for governing the reciprocating motion of said 15 funnels.

In testimony whereof I affix my signature.

ALFRED LEHNER.
